Henry D. Williams
ATTORNEY

UNITED STATES PATENT OFFICE.

HARRY CLINTON GOODRICH, OF FORT LEE, NEW JERSEY.

PACKAGE-CARRIER.

1,291,479.

Specification of Letters Patent. Patented Jan. 14, 1919.

Application filed April 13, 1915. Serial No. 21,152.

To all whom it may concern:

Be it known that I, HARRY CLINTON GOODRICH, a citizen of the United States, residing at the borough of Fort Lee, in the 5 county of Bergen and State of New Jersey, have invented certain new and useful Improvements in Package-Carriers, of which the following is a specification, reference being had therein to the accompanying drawings, forming part thereof.

My invention relates to fastening devices for package carriers and objects of my invention are to provide a simple inexpensive and effective device of this kind adapted to 15 be attached to a strap for carrying packages of books and also other bundles or articles which it is desired to assemble and retain in a single package provided with convenient means for carrying in the hand. 20 Other more particular objects and advantages of my invention will hereinafter appear.

My invention includes a particular construction of fastening device embodying 25 novel features of construction, as will appear from the following description.

I shall now describe the fastening device embodying my invention illustrated in the accompanying drawings and shall there- 30 after point out my invention in claims.

Figure 1 is a perspective view illustrating the use of a package carrier embodying my invention.

Fig. 2 is an enlarged partial elevation 35 of the package carrier as viewed diagonally from the front and right in Fig. 1.

Fig. 3 is a further enlarged perspective view of one end of the package carrying strap and the fastening device thereon.

40 Fig. 4 is a reversed plan or view from the back of what appears in Fig. 3.

Fig. 5 is a perspective edge view of a fastening device before its attachment to the carrier strap.

45 Fig. 6 is a front plan view of a sheet metal blank cut out in its final shape or configuration but not yet bent to form the completed fastening device.

Fig. 7 is a plan view illustrating a slightly 50 modified construction of fastening device.

The package carrier embodying my invention illustrated in the accompanying drawings comprises a package-encircling and handle-providing strap 1 having similar 55 strap-engaging or strap-gripping fastening devices securely anchored or permanently

attached to each end thereof as shown in the drawings. The strap 1 may be of any suitable material but is preferably composed of strong and heavy woven webbing and 60 that is the material indicated in the drawings.

The fastening devices carried by the ends of the strap 1 are shown in the drawings as of identical construction and a single particular description will therefore serve for each of the two devices embodied in the complete package carrier illustrated in the drawings. Each fastening device is shown as formed from a single piece of sheet metal 70 and in manufacture a flat blank is first punched out of the shape illustrated in Fig. 6 and this flat blank is bent along the broken lines indicated in Fig. 6 to form the completed fastening device which appears in 75 Fig. 5 before its attachment to the strap 1 and in the other figures of the drawings two such fastening devices are shown as permanently attached or anchored to the strap 1.

80 Each fastening device has a flat main portion or body 2 which is narrower at the rear and of greater width in its forward portion. Attaching lugs or anchor lugs 3 are provided at each side at the rear of the 85 body 2 and these attaching lugs are turned over toward the back so as to project substantially perpendicularly to the body 2 before the fastening device is attached to the strap 1 as appears in Fig. 5 and which in 90 the attached or final and complete condition of the package carrier are clenched tightly at the back upon the end of the strap 1 as appears in Figs. 1, 2, 3 and 4 of the drawings, particularly in Fig. 4, thereby securely 95 to anchor the fastening device in place upon the end of the strap 1.

100 In its wider portion forward from the attaching lugs 3 the body 2 is provided with a transverse gripping slot 4 which is open at one of its ends at one edge of such wider portion of the body 2 so as to be adapted to snugly slip over and detachably grip the strap 1 at any desired place along such strap and as is clearly illustrated in Figs. 1 and 105 2 of the drawings. A strap-tightening lug 5 projects to the front at the rear of the body 2 between the attaching lugs 3 and is adapted to be engaged by the thumb for shifting the fastening device longitudinally 110 along the strap 1 in tightening the strap about a package, and also in adjusting the

free portion of the strap to form a handle loop as shown in Figs. 1 and 2. A side lug 6 projects to the front at the side edge of the body 2 adjacent to the closed end of the strap-gripping slot 4, this side lug 6 being engageable by the forefinger and thumb for slipping the fastening device into place on the strap 1 with the strap in the slot 4, or for effecting the disengagement of the fastening device from the strap 1. It will be noted that the strap-gripping slot 4 is of greater length than the width of the strap 1 which is to be engaged therein thereby providing greater security of engagement. The wider slotted gripping portion of the body 2 and the projecting attaching lugs 3 are formed from adjacent lateral parts of the flat metal, thereby utilizing the metal to good advantage with a minimum of waste, as will be most clearly evident from an inspection of Fig. 6 of the drawings. It should also be noted that preferably the manually engageable lugs 5 and 6 project substantially perpendicularly from the body 2 as appears in the drawings. It should be further noted that not only, as hereinbefore stated, are both of the fastening devices alike at the two ends of the strap, but they are attached to the strap in the same relative positions as viewed from the same side of the strap, that is to say, Fig. 3, for example, is a correct illustration of either end of the carrier strap 1 and its attached fastening device.

The manner of use and operation of the package carrier are clearly indicated in Fig. 1. In placing the package carrier on a package, the strap 1 is passed around the one or more articles which are to form the package, such, for example as the books shown in Fig. 1, and one of the fastening devices, for example that shown at the right in Fig. 1, is slipped over the adjacent edge of the strap 1 so that the strap fully enters the gripping slot 4, the finger being pushed against the side lug 6 in effecting such engagement. The fastening device is then slipped along the strap 1 to tighten the strap about the package, the thumb pressing against the rear lug 5 in effecting such tightening of the strap. The slot 4 has square-cut edges or side walls, as indicated in the drawings, and fits closely or snugly over the strap 1 so that the angular tension of the strap, as clearly illustrated at the right in Fig. 2, produces an effective gripping action so that the tightened strap will not slip

through the slot 4 after the proper adjustment has been made. The fastening device at the other end of the strap is now engaged with the strap 1 at the proper place to form a handle loop for the package, as clearly appears in Figs. 1 and 2, and such handle loop will, of course, be somewhat longer or shorter according to the dimensions of the package which is encircled by the strap.

In the slightly modified construction illustrated in Fig. 7 the wider forward portion of the central body 7 stops at the gripping slot 8 adjacent to the open end of such slot so as to leave a projecting prong 9 forward from the slot. This prong 9 makes it easier to engage the strap in the slot 8. In some instances this modified construction might be desirable.

It is obvious that various modifications may be made in the constructions shown in the drawings and above particularly described within the principle and scope of my invention.

I claim:

1. A fastening device formed from a single piece of flat metal and comprising a flat body, attaching lugs projecting at opposite edges of the body at the rear thereof and adapted to be clenched to anchor the device in place, such body being of greater width forward from the anchor lugs and provided in such wider portion with a transverse gripping slot open at one edge of said wider body portion, whereby such wider slotted gripping portion and the projecting attaching lugs may be formed from adjacent parts of the flat metal.

2. A fastening device including a single piece of metal and comprising a flat body, attaching lugs projecting toward the back at opposite edges of the body at the rear thereof and adapted to be clenched to anchor the device in place, such body portion being provided with a transverse gripping slot open at one edge of said body portion, a rear manually engageable lug projecting to the front rearward from the attaching lugs, and a side manually engageable lug projecting to the front at the edge of said body portion adjacent to the closed end of the gripping slot.

In testimony whereof I have affixed my signature in presence of two witnesses.

HARRY CLINTON GOODRICH.
